DESIGN FOR LACE

David L. Peister, New York, N. Y.

Application August 6, 1941, Serial No. 102,702

Term of patent 3½ years

To all whom it may concern:

Be it known that I, David L. Peister, a citizen of the United States of America, residing at 144 West 86th Street, New York city, county and State of New York, have invented a new, original, and ornamental Design for Lace, of which the following is a specification, reference being had to the accompanying drawing, forming a part thereof.

The figure is a plan view of lace showing my new design, the same being illustrated on a dark background to bring out more clearly the open-work and each outline of the design.

I claim:

The ornamental design for lace, as shown and described.

DAVID L. PEISTER.
